(57) **CLAIM**

The ornamental design for an audio component, as shown and described.

DESCRIPTION

FIG. 1 is a perspective view of an audio component, specifically an audio mixing console, showing our new design;

FIG. 2 is top plan view thereof;

FIG. 3 is a side elevational view thereof;

FIG. 4 is a rear elevational view thereof;

FIG. 5 is a front elevational view thereof; and,

FIG. 6 is a bottom plan view thereof.

The heavy uneven broken line depicts a boundary of the claim and does not form part of the claimed design. The broken line showings depict environmental features which form no part of the claimed design.
